COMMERCIAL DISH WASHER RACK

Sol Kesilman, 7930 Oak Hill Drive, Cheltenham, Pa.;
Hyman B. Penn, 435 Twickenham Road, Glenside, Pa.;
and Milton Kravitz, 6710 Large St., Philadelphia, Pa.

Filed Jan. 30, 1964, Ser. No. 78,426

Term of patent 14 years

(Cl. D49—1)

FIG. 1

FIG. 5

Des. 201,383

PAGE 2

FIG. 2

FIG. 3

FIG. 4

FIG. 1 is a top plan view of a first embodiment of a commercial dish washer rack, showing our new design.

FIG. 2 is a bottom plan view thereof.

FIG. 3 is a side elevational view thereof.

FIG. 4 is a sectional view thereof, taken along the line 4—4 of FIG. 1.

FIG. 5 is a front elevational view thereof.

FIG. 6 is a quarter section perspective view thereof, taken along the line 6—6 of FIG. 1.

FIG. 7 is a quarter section perspective view, similar to FIG. 6, of a second embodiment of a commercial dish washer rack, showing our new design.

We claim:

The ornamental design for a commercial dish washer rack, substantially as shown and described.
